UNITED STATES PATENT OFFICE

GEORGE S. HILTZ, OF BROOKLYN, NEW YORK, AND WILLIAM F. PURCELL, OF HOBOKEN, NEW JERSEY, ASSIGNEES TO STOCK QUOTATION TELEGRAPH COMPANY, OF NEW YORK, N. Y., A CORPORATION OF NEW YORK

PRINTING TELEGRAPH

Application filed November 28, 1927. Serial No. 236,086.

This invention relates to an improvement in printing telegraphs in which a transmitter is employed in connection or cooperation with any number of recording machines which record the characters sent out by the transmitter, and the invention has for one of its objects, the provision of an improved mechanism whereby the recording machines may be brought automatically into unison as often as desired.

In printing telegraphs as now constituted, the operator at the transmitter is supposed to operate a key or switch at intervals which will bring about a unisoning of the recording machines, but in actual practice, the operator sometimes fails to do this with the result that a recording machine once out of unison may remain in that condition for an extended period.

By the present arrangement we have provided a construction whereby the unisoning of the machine is brought about by the closing of a predetermined circuit, effected in the present instance by manipulation of the period or spacer key on the transmitter, and inasmuch as this key is depressed very frequently by the operator of the transmitter, it will be obvious that the recording machines will be brought to unison at sufficiently short intervals to make our apparatus practicable.

In the operation of machines of the character with which the present invention is concerned the current employed is reversed in polarity automatically for the purpose of effecting operation of escapement magnets constituting a part of the recording machine, the operation of these magnets causing the escapement mechanism which controls the rotation of the shaft carrying the type wheels to function. To operate the impressing mechanism of the receiver, an impress magnet is employed operative when the transmitter shaft has been brought to rest, at which time current of one polarity only is flowing through the line. In the present invention, resistance normally in series with the escapement magnets, is adapted, when the machines are to be brought to unison, to be shunted on the closing of a predetermined circuit as by the operation of the period or

spacer key of the transmitter, whereby the operator, in the normal and ordinary operation of the transmitter will unison the recording machines intermittently although not necessarily at regular intervals.

In the accompanying drawings wherein an embodiment of our invention has been illustrated,

Fig. 1 shows the same in side elevation; Fig. 2 is a plan view of the apparatus of Fig. 1;

Fig. 3 is a view similar to Fig. 2, this view being taken at right angles Fig. 2;

Figs. 4, 5, 6 and 7 are detail views; and Fig. 8 is a wiring diagram.

Our improved apparatus comprises scape wheel 1, and escapement pawl 2 adapted to be vibrated in the usual way by the armature 3 of escapement magnets 4 and 5. These magnets, as is well known, effect a vibration of the armature 3, because of a reversal of the polarity of the current passing through the magnets, this reversal of polarity being effected by polar relay 6, (see the wiring diagram of Fig. 8). The scape wheel is mounted upon a rotatable shaft 7, which shaft carries also a worm 9, and a unisoning arm 10, the latter extending at right angles to the longitudinal axis of the shaft and being provided at its outer end with a cam face 11. Pivotally secured to the frame of the machine as at 12, for example, is an arm 13 which extends toward the type shaft 7 so that its inner end overlies the same, this end of the arm being provided with a portion 14 adapted to cooperate with the worm 9. The portion 14 is provided with a stop pin 15, extending laterally with respect to the arm, this pin being disposed at right angles to the plane of rotation of the unisoning arm 10 heretofore referred to. Attached to the stop arm 13 is a spring 16 anchored to the frame of the machine at 17, this spring tending to draw the outer end of the arm 13, i. e., the end carrying the stop pin 15 to the right, as shown in Fig. 3, for instance, and into engagement with the worm 9.

The escapement magnet 5 has its poles extended as indicated at 18, for cooperation under certain conditions with an armature

19 which is pivoted at 20, which armature 19 is held in normal position by a spring 21 anchored at 22. The inner end of this armature overlies the extension 18 of the poles of 5 the magnet 5, while the outer end is provided with an upwardly extending portion 23 lying beneath the end of the pivoted arm 13.

As above explained, the purpose of this 10 simple means for bringing the recording machines into unison with the transmitter, consequently it is possible by our construction, to stop the rotation of the type shaft 7 periodically with the deliberate intention of 15 unisoning the machines. The stopping of the type shaft 7 is brought about by interposing the pin 15 in the path of the arm 10, carried by the type shaft.

With reference now to the wiring diagram 20 of Fig. 8, we have illustrated therein diagrammatically a transmitting machine comprising the usual sunflower or stationary commutator 24, trailer 25 cooperating therewith and mounted on a trailer shaft 26, which is 25 geared to the transmitter shaft 27, magnetic clutch 28, keyboard 29, and relay 30 for the clutch. The keyboard is shown as provided with two keys 32 and 33, but it will be understood, of course, that in practice it is provided 30 with the usual number of keys for controlling the transmitter.

In the operation of the machine, with the transmitter shaft 27 in rotation the polarity 35 of the current passing through the escapement magnets 4 and 5 is reversed in the usual way by the provision of the brushes 34, 35 and 36, cooperating with the polar relay 6 to effect vibration of the armature 3 of the escapement magnets of the receiving instrument, (see Fig. 1), and a resulting vibration 40 of the escapement pawl 2 to permit the scape wheel 1 to rotate in an intermittent fashion. When the key 32, for instance, of the transmitter keyboard is operated, a circuit is closed 45 to the clutch relay 30; the armature 37 of this relay is operated to close a circuit to the magnetic clutch 28, the closing of this circuit arresting the rotation of the transmitter shaft 27. Under these conditions the impress 50 magnet 31 of the receiving instrument will operate to effect operation of the impress mechanism to make the desired impression.

In the operation of this apparatus, the 55 end 14 of the arm 13 (Fig. 3) will lie upon the worm 9 and inasmuch as the same is rotating intermittently by the action of the escapement mechanism, the arm will be moved to the left by the action of the worm toward the scape wheel to the dotted line position, 60 for example, shown in Fig. 7. Assuming that when the arm 13 has reached the position shown in Fig. 7, the period key 33 is depressed, the electromagnet 38 (Fig. 8) will receive current so as to shunt resistance 39 65 which, up to this time, has been in series with

the electromagnets 4 and 5. Of course, the depression of the period or spacer key 33 will also close the circuit to the magnetic clutch 28, as will be understood, so that the polar relay 6 will no longer be operative and a current of only one polarity and of increased amperage will flow through the magnets 4 and 5, and this increase in current will cause the magnet 5, to attract the armature 19 (see Fig. 4). The swinging of the armature 19 about its pivot will raise the inner end of the arm 13 as shown in Fig. 4, so as to lift the end 14 out of engagement with the worm 9 on the type shaft and the spring 17 which has been placed under some tension due to the movement of the arm 13 to the left, as viewed in Fig. 3, will draw the end of this arm to the right, as viewed in the same figure, in a direction away from the scape wheel 1 and toward the unisoning arm 10. If the machine is in unison, as the arm 13 is moved toward the unisoning arm 10, the latter will be in the position shown in Fig. 6, i. e., in such a position that the stop pin 15 as the arm 13 drops downward will strike the cam face 11 on the unisoning arm 10 and this face will cam the arm 13 to the left again, as viewed in Fig. 6, until the arm is free to fall upon the worm 9 to again resume its normal travel toward the scape wheel. In other words, if the machine 95 is in unison with the transmitter, upon the depression of the key 33 the unisoning mechanism will have no effect upon the type shaft 7. If, however, the machine should be out of unison, the unisoning arm 10 will be in such a position when the end 14 of the arm 13 is moved to the right, as viewed in Fig. 7, that the cam face 11 will not be effective to move the pin 15 and arm 13 toward the scape wheel and the pin 15 will remain in the path of the unisoning arm 10 to prevent rotation of the type shaft 7. The type shaft 7 will remain stationary until the period or spacer key 33 is again depressed at which time, of course, the transmitting machine and the receiving machine will be in unison. The depression 100 of the period or spacer key 33 the second time will, of course, raise the end 14 of the arm 13 and inasmuch as the unisoning arm 10 is now at the pin 15, the pin 15 will be raised into engagement with the cam face 11 on the arm 10, and this unisoning arm now being free to rotate, it and the type shaft will rotate in the direction of the arrow on Fig. 7, and the face 11 will cam the arm 13 to the left out 105 of the path of the arm 10 entirely, and the end 14 of the arm 13 will fall upon the worm 9 to resume its normal travel to the left or toward the scape wheel.

It will be seen, therefore, that we have 110 provided an apparatus for use in connection with printing telegraphs whereby the receiving machine may be brought to unison by the closing of a predetermined circuit, it being understood that depression of the spacer key 115

for this purpose has been shown for purposes of illustration only. It is to be understood also that if desired, means other than the escapement magnet may be provided for disengaging the stop arm from the worm or other means on the type shaft. It will be seen also that the unisoning mechanism is capable of arresting the rotation of the type carrier shaft when the machine is out of unison but is carried automatically out of shaft arresting position if the machine is in unison. Likewise it will be apparent that means have been provided whereby when the type shaft has been stopped by our unisoning mechanism, and the machine brought to unison, the mechanism is then operative to permit of the type shaft resuming its rotation.

It will be understood that various modifications may be made in the construction above described within the purview of this invention.

What we claim is:—

1. In printing telegraph receivers, a type shaft, a unisoning arm affixed thereto, a stop pin, means for causing the rotation of said type shaft to effect movement of said stop pin away from the unisoning arm, means for bringing the stop pin into engagement with said arm to arrest the movement of the type shaft when the machine is out of unison, and means for releasing the stop pin from engagement with the unisoning arm when the machine has been brought to unison.

2. In printing telegraph receivers, a type shaft, a unisoning arm affixed thereto, a stop pin, a worm rotatable with the type shaft for effecting movement of said stop pin away from the unisoning arm, means for bringing the stop pin into engagement with said arm to arrest the movement of the type shaft when the machine is out of unison, and means for releasing the stop pin from engagement with the stop arm when the machine has been brought to unison.

3. In printing telegraph receivers, a type shaft, a unisoning arm affixed thereto, a stop pin, means for causing the rotation of said type shaft to effect movement of said stop pin away from the unisoning arm, means for bringing the stop pin into engagement with said arm to arrest the movement of the type shaft when the machine is out of unison, means for releasing the stop pin from engagement with the unisoning arm when the machine has been brought to unison, and means for preventing the stop pin from arresting the movement of the type shaft when the machine is in unison.

4. In printing telegraph receivers, the combination of a type shaft, a unisoning arm carried thereby, a stop pin cooperating with said arm to arrest the movement of the type shaft when the machine is out of unison, said arm being provided with a cam for moving

the pin out of arresting position when the machine is in unison.

5. In printing telegraph receivers, the combination of a type shaft, a pivoted arm, a stop pin carried by said arm, a unisoning arm cooperative with said stop pin, means operative by the type shaft for moving the stop pin away from said unisoning arm, and a spring for moving the stop pin in the opposite direction when the machine is to be brought to unison. 70

6. In printing telegraph receivers, unisoning mechanism comprising a unisoning arm, a stop pin cooperating therewith, means for moving said stop pin away from said unisoning arm and a spring for moving the arm toward said pin. 80

7. In printing telegraph receivers, unisoning mechanism comprising a unisoning arm, a stop pin cooperating therewith, a spring for moving said pin into operative position relative to said arm, and a cam for moving the pin away from said arm when the machine is in unison. 85

8. In printing telegraph receivers, unisoning mechanism comprising a unisoning arm and a worm rotatable with the type shaft of the machine, a stop arm adapted to engage said worm, a stop pin carried by said stop arm, the rotation of said worm carrying the stop pin away from said unisoning arm, and a spring adapted to move said stop pin in the opposite direction to arrest the movement of the unisoning arm and type shaft when the machine is out of unison. 90

9. In printing telegraph receivers, unisoning mechanism comprising a unisoning arm and a worm rotatable with the type shaft of the machine, a stop arm engageable with said worm and adapted to be moved thereby in a direction away from the unisoning arm, means for raising the stop arm out of engagement with said worm, a spring operable when the stop arm is so raised to move the stop arm toward the unisoning arm, and a pin carried by the stop arm adapted to be engaged by the unisoning arm to stop the type shaft when the machine is out of unison. 105

10. In printing telegraph receivers, unisoning mechanism comprising a worm on the type shaft, a stop arm, a unisoning arm on said type shaft, a stop pin carried by the stop arm, said stop arm being engageable with said worm to be moved thereby away from the unisoning arm, an electromagnet, an armature therefor operatively connected to said stop arm and adapted to raise the same out of engagement with said worm, and a spring for moving the stop arm when the same is raised toward the unisoning arm to bring the stop pin into the path of the unisoning arm. 115

11. In printing telegraph receivers, unisoning mechanism comprising a stop arm, a stop pin carried thereby, a unisoning arm rotata- 120
125
130

ble with the type shaft of the machine, means on the type shaft for moving said stop arm and pin away from the unisoning arm, a spring opposing this movement, an electromagnet for actuating the stop arm to permit the spring to move the same and its pin toward the unisoning arm, said pin lying in the path of the unisoning arm when the machine is out of unison to arrest the movement of the type shaft, said unisoning arm being provided with a cam face for engaging said pin when the machine is in unison to move the stop arm and pin away therefrom.

12. In printing telegraph receivers, the combination of a type shaft, a worm carried thereby, a pivoted stop arm overlying said worm and having a portion thereof engageable with said worm, a stop pin carried by said stop arm, a unisoning arm carried by the type shaft, the engagement of the stop arm therewith moving said stop pin away from the unisoning arm, an electromagnet, an armature therefor adapted to move the stop arm out of engagement with the said worm, a spring attached to said arm to move the same toward the unisoning arm and the pin into the path thereof when the stop arm and worm are disengaged, said pin remaining in the path of said unisoning arm when the machine is out of unison, said unisoning arm having a cam face engageable with the stop pin to force the same out of its path when the machine has been brought to unison.
